TELEPHONE JACK

Joseph Ratner, 225 W. 106th St.,
New York, N.Y. 10025

Filed June 6, 1967, Ser. No. 7,378

Term of patent 3½ years

(Cl. D26—1)

FIG. 1

FIG. 2

FIG. 3

FIG. 4

FIG. 6

FIG. 7

FIG. 5

FIGURE 1 is a perspective view of the telephone jack, showing my design.

FIGURE 2 is a side elevation view of the telephone jack of FIGURE 1.

FIGURE 3 is a front view of the telephone jack of FIGURE 1.

FIGURE 4 is a rear view of the telephone jack of FIGURE 1.

FIGURE 5 is a bottom view of the telephone jack of FIGURE 1.

FIGURE 6 is a section view taken along line 6—6 of FIGURE 3.

FIGURE 7 is a section view taken along line 7—7 of FIGURE 3.

The dominant features of my design reside in the portions shown in full lines in the drawing.

I claim:

The ornamental design for a telephone jack, as shown and described.
